(57) **CLAIM**

The ornamental design for a self-adhering bead device as shown and described.

DESCRIPTION

FIG. 1 is a perspective view of the self-adhering bead device;

FIG. 2 is an end view of the self-adhering bead device;

FIG. 3 is another end view of the self-adhering bead device;

FIG. 4 is a side view of the self-adhering bead device;

FIG. 5 is another side view of the self-adhering bead device;

FIG. 6 is a back side view of the self-adhering bead device; and,

FIG. 7 is a front side view of the self-adhering bead device. The broken lines are for the purpose of illustrating boundaries and portions of the self-adhering bead device that form no part of the claimed design. The appearance of any portion of the self-adhering bead device between the break lines shown in FIGS. 1 and 4-7 forms no part of the claimed design.
